UNITED STATES PATENT OFFICE.

WILLIAM E. PAYNE, OF OWOSSO, MICHIGAN.

TUBE-CLAMP.

1,055,552.

Specification of Letters Patent. Patented Mar. 11, 1913.

Application filed May 27, 1912. Serial No. 699,893.

To all whom it may concern:

Be it known that I, WILLIAM E. PAYNE, a citizen of the United States, residing at Owosso, in the county of Shiawassee and State of Michigan, have invented certain new and useful Improvements in Tube-Clamps; and I do hereby declare the following to be a full, clear, and exact description of the invention, such as will enable others skilled in the art to which it appertains to make and use the same.

This invention relates to clamps used for securing patches to the air tubes of wheel tires; and it consists in the novel construction and combination of the parts hereinafter fully described and claimed.

In the drawings, Figure 1 is a plan view of a clamp constructed according to this invention. Fig. 2 is a side view of the clamp, showing one of its plates in section on the line $\alpha-\alpha$ in Fig. 1.

The clamp is formed of two opposed plates 2 and 3. The plate 2, which is longer than the plate 3, has a pair of lugs 4 at one end portion, and a shorter pair of lugs 5 at its other end portion.

The plate 3 has a tongue 6 at one end which projects in the space between the pair of lugs 4. At the other end of the plate 3 a tongue 7 is provided which projects in the space between the pair of lugs 5 and which has a series of grooved steps 8 on its upper side. The plate 3 is movable longitudinally upon the plate 2, and 10 is a pin which is passed through holes in the pair of lugs 5 and which engages with one of the grooved steps. The grooves are made in the form of steps, so as to vary the thickness of the tongue, and thereby enable the same

clamp to be used for tubes of different thickness of material.

An eccentric or cam 14 is pivoted to the pair of lugs 4 by a pin 15, and is arranged over the tongue 6. A long handle 16 projects from the eccentric 14. When a patch is to be cemented over a puncture in the air tube 8 of a vehicle tire, the tube together with the patch piece and some suitable cement between them is compressed between the two plates, as shown in Fig. 2, and the patch piece is held to the tube over the puncture until the cement has hardened. The handle is moved to apply the clamp, and the eccentric is turned to a position from which it cannot slip and in which it is held by frictional contact with the tongue.

What I claim is:

In a tube clamp, the combination, with a flat plate of rigid material having two pairs of lugs of unequal height which project upwardly from the opposite end portions of its upper surface, of a longitudinally adjustable flat plate of rigid material having tongues at its ends which project longitudinally between the said pairs of lugs, one of the said tongues having a series of grooves stepped in relation to its under face, a pin carried by the short lugs and engaging with the said grooves and holding the grooved tongue in place, and an eccentric pivoted to the long lugs and bearing on the other tongue.

In testimony whereof I have affixed my signature in the presence of two witnesses.

WILLIAM E. PAYNE.
